UNITED STATES PATENT OFFICE.

GEORGE B. EDINGER AND JOHN S. MCCOY, OF FOXBURG, PENNSYLVANIA.

ELECTRICALLY-OPERATED CONTROL MECHANISM FOR RETAINER VALVES.

Application filed August 6, 1921. Serial No. 490,433.

To all whom it may concern:

Be it known that we, GEORGE B. EDINGER and JOHN S. MCCOY, citizens of the United States, residing at Foxburg, in the county of 5 Clarion and State of Pennsylvania, have invented certain new and useful Improvements in Electrically-Operated Control Mechanisms for Retainer Valves, of which the following is a specification, reference being had 10 to the accompanying drawings.

This invention relates to air brake systems, and particularly to retaining valves therefor.

Retaining valves, as is well known, are for 15 the purpose of retarding the release of the air from the brake cylinder and to retain a pressure of a certain number of pounds in the brake cylinder while the engineer is recharging the auxiliary reservoir prepara- 20 tory to another application of the brakes.

The general object of the present invention is to provide means whereby an engineer of a train may, if he so desires, prevent the free and unobstructed passage of 25 air from the exhaust port of the triple valve and cause this air to pass into the retaining valve to thereby retain a certain amount of pressure in the brake cylinders and whereby if the engineer so desires the free and un- 30 obstructed exhaust or the air from the brake cylinders may be permitted.

A further object is to do away with the necessity of trainmen shifting the retaining valves of the train while the train is in motion to thereby put the retaining valves into or out of commission and provide means whereby the retaining valves of all of the cars are controllable by the engineer.

A still further object is to operate the exhaust controlling valve by means of a magnet or solenoid supplied with current from the dynamo with which all engines are equipped, the circuit which includes all of these solenoids or magnets including a 45 switch disposed in the cab of the engineer whereby the engineer may close the electrically operated exhaust valves of all the cars at one time or cause the opening of these exhaust valves at one time.

50 Another object is to provide a device of this character which does away with the possible chance of a retaining valve being set in wrong position or carelessly forgotten to

be released, thus saving coal and reducing the number of flat wheels.

Other objects will appear in the course of the following description.

Our invention is illustrated in the accompanying drawings, wherein:—

Figure 1 is a diagrammatic view illustrating the ordinary and usual air brake mechanism of a car and illustrating in elevation our electrically actuated exhaust valve applied in connection with the retaining valve;

Figure 2 is a longitudinal sectional view 65 of the exhaust or release valve showing the valve in its open position;

Referring to these drawings, it will be seen that in Figure 1 I have illustrated diagrammatically a part of the air brake mechanism of an ordinary car. In these drawings, 10 designates the auxiliary reservoir, 11 the brake cylinder, 12 the triple valve body generally, 13 the pipe connecting the triple valve body to the brake cylinder, 14 the pipe leading from the triple valve body to the train pipe 15, and 16 the retaining valve casing from which a pipe 17 leads to the exhaust port or chamber 18 of the triple valve. All of these parts are of any ordinary or usual construction and therefore demand no detailed description.

We have shown a conventional form of triple valve, and it will be understood that any triple valve may be used and any type 85 of retaining valve may be used. The retaining valve is assumed to be that type which is capable of being set to retain a definite pressure within the brake cylinder and that releases air above this pressure 90 and closes when the pressure in the brake is reduced to the amount for which the retaining valve is set. Disposed in the pipe 17 is a T 19, from which extends a pipe 20 which enters into the valve casing 21 midway of its ends, this valve casing 21 being open at its ends and provided with the spiders 22 forming guides for a valve rod 23. The valve casing is formed to provide two valve seats 24, through the center of 100 which the valve rod or spindle 23 passes, and carried upon this valve rod or spindle are a pair of valves 25 coacting with said seats 24. When the rod 23 is shifted in one direction, the valves 25 will close against 105 the seats 24 and free outlet from pipe 20 is

prevented. On the other hand, the spring 26 acts normally to urge the valve rod 23 in a direction to hold the valves in an open position, giving a free and unobstructed 5 exhaust to the air.

For the purpose of actuating this valve 23, we provide an electro-magnet preferably in the form of a solenoid and designated 27, and attach to the valve stem or rod 23 the 10 core 28 of the solenoid. It will be obvious now that when the solenoid is energized by the passage of an electric current, the core 28 will be drawn up within the solenoid and the valves 25 will be closed against the 15 seat 24 and against the action of the spring 26. When the magnet, however, is de-energized, the spring 26 will cause the opening of the valves 25. This solenoid 27 is connected in circuit with a source of current, 20 as for instance a generator on the engine, but which source of current is symbolized as a battery 29 and in this circuit is disposed the switch 30. This switch is located in the engineer's cab so that when the switch 25 is closed the electric current will pass through the solenoid and when the switch is opened the current will cease to flow. It is to be understood that while we have 30 illustrated one solenoid 27 disposed within the circuit including the switch 30 and the battery 29, yet it is intended that all of the solenoids of the train shall be connected in circuit with this single switch 30 or, if desired, that a number of solenoids in the 35 train may be so connected to the switch, so that as regards any desired number of cars the valves 25 may be closed upon an energizing of their respective magnets.

The operation of this mechanism will be 40 obvious from what has gone before. When the triple valve is shifted by the usual mechanism to release the air in the brake cylinder 11, which is the position of the triple valve shown in Figure 1, the air from the brake cylinder will pass along the pipe 17 and if the valves 25 be in open position, the air will exhaust to the atmosphere through the ports 24 and the open ends of the valve body 21. If, however, it be desired that 45 the retaining valve mechanism shall become operative, then the engineer closes the circuit through the solenoid 27 and thereby energizes these magnets, causing the cores 28 to be drawn up within the solenoid, which 50 closes the ports 24, prevents the free and unobstructed passage of the air from the brake cylinder to the atmosphere, and causes the air from the brake cylinder to act upon the usual retaining valve so that a definite 55 pressure will be retained within the brake cylinder in the usual manner. It will be obvious therefore that when the valves 25 are closed that the retaining valve performs 60 its ordinary functions, but that when these 65 valves 25 are opened that the retaining valve

is in effect cut out and the exhaust is allowed to flow directly to the atmosphere. Attention is called to the fact that the valves 25 are balanced valves so that any pressure which would tend to close one valve tends 70 to open the other valve and that thus the valve stem is balanced and the pressure will not act to open the valves. The same is true as to the closing of the valves and the valves will only be affected by the energizing of 75 the solenoid. It is for this reason that we have shown two valves disposed in the casting 21.

We do not wish to be limited to the particular form of valves and valve casing 80 which is disclosed in Figure 2, nor to the particular electrically actuated means whereby the valve is shifted, as modifications might be made and the device changed in detail in many respects without departing 85 from the principle of the invention. It will be seen that this construction is particularly simple and cheap and that it may be readily applied to air brake systems now in use without the change of any essential feature 90 therein. The device places the control of the retaining valve entirely in the hands of the engineer and he can either cause the use of the retaining valves under certain 95 conditions for a short time or he can put the retaining valves in operation for as long a period as he desires. The current, as before stated, is supplied by the ordinary dynamo or generator found on all trains today and the wire conveying current to the several 100 solenoids may be so connected that coupling may be made between the cars at the time when the trainline is coupled up between the cars.

This device does away with the chance 105 of one or more retainer valves in a train being set in wrong position or carelessly forgotten to be shifted to a release position. This saves a large amount of coal, as where retainer valves are not shifted to released 110 position the engine must pull the train against the action of the brakes. It also thus prevents the flattening of wheels. Also where releasing brake when the speed 115 of the train is below the speed point, retainers can be used, thus relieving strain on the draw bars.

It is to be particularly noted that in this device we have provided a balanced valve 120 25 which will shift to normal position without needing the assistance of the spring 26, this valve being so balanced that the pressure 125 on the lower piston, which acts to shift the valve to its open position, is slightly greater than the pressure on the upper piston holding the valve to the closed position. This difference is very slight and in practice a difference of $1/20$ of 1% will cause the movement of the valve to its open position. This difference is not enough to move the valve 130

alone against the friction of the valve when there is low pressure and it is then that the spring is necessary. This tension, however, is very slight and the resistance to the action of the magnet is very slight, due to the valve being balanced in this manner. This construction insures the valve going to its normal or open position in case the spring should break.

10 We claim:—

1. The combination with the retaining valve of an air brake system and an exhaust connection leading to said valve, of a valve controlling passage of the exhaust in said

15 connection to the outside air, and electrically operated means for controlling said valve.

2. In an air brake system, the combination with a retaining valve and an exhaust connection leading thereto of a valve con-

20 trolling communication between said connection and the outside air and normally held in an open position, and electrically ener-

gized means closing said valve.

3. In an air brake system, the combina-
25 tion with a retaining valve and an exhaust connection leading thereto, of a valve casing communicating with said exhaust connection and with the outside air, a normally open valve in the valve casing, and elec-
30 trically operated means acting when ener-
gized to close said valve.

4. In an air brake system, the combination with a retaining valve and an exhaust connection leading thereto, of a valve casing

35 communicating with said exhaust connection and with the outside air, a normally open valve in the valve casing, and electrically operated means acting when energized to close said valve and including a solenoid, and a

40 coacting core operatively connected to the valve.

5. In an air brake system, a retaining valve, an exhaust connection leading there-
to, a valve casing having a port connected

to the exhaust connection and a port lead- 45 ing to the exterior air, a valve in the valve casing coacting with said port, yielding means holding said valve in an open position, and electro-magnetically operated means for closing said valve and including 50 a switch in the engine cab.

6. In an air brake system, a retaining valve, an exhaust connection leading there-
to, a pipe leading from said exhaust con- 55 nection, a valve casing into which the pipe opens and open at its ends to the exterior air, a pair of valve seats disposed in said valve casing, a pair of connected valves co-
acting with the valve seats, a valve rod on 60 which the valves are mounted, a spring en-
gaging the valve rods and normally holding the valves in an open position and away from said seats, and electrically controlled means for shifting said valves against the seats to cut off communication to the out- 65 side air.

7. In an air brake system, a retaining valve, an exhaust connection leading there-
to, a pipe leading from said exhaust con- 70 nection, a valve casing into which the pipe opens and open at its ends to the exterior air, a pair of valve seats disposed in said valve casing, a pair of connected valves co-
acting with the valve seats, a valve rod on 75 which the valves are mounted, a spring en-
gaging the valve rods and normally holding the valves in an open position and away from said seats, and electrically controlled means for shifting said valves against the seats to cut off communication to the outside 80 air and including a solenoid electrically connected in circuit with a source of current and the switch, and a core operatively connected to the valve rod.

In testimony whereof we hereunto affix our 85 signatures.

GEO. B. EDINGER.
